By his Attorney *Reich Schucht*

UNITED STATES PATENT OFFICE.

ANTON STÖGER, OF LONG ISLAND CITY, NEW YORK, ASSIGNEE TO AMERICAN MOTION PICTURE MACHINE WORKS, OF LONG ISLAND CITY, NEW YORK, A FIRM COMPOSED OF ANTON STÖGER AND EDMUND WISNIEWSKI.

COMBINED RHEOSTAT AND SWITCH.

Application filed May 17, 1922. Serial No. 561,605.

The invention relates to resistance changing mechanism or rheostats, for example of the type now extensively employed in connection with the control of the filament current of vacuum tubes used in radio communication. In such rheostats it is especially desirable to afford means for rather fine adjustment of the resistance, as well as to provide for the cutting off entirely of the lamp current at certain times.

The present invention has for its object a rheostat wherein a micrometer adjustment of the resistance is afforded and wherein the current may be entirely cut off; and in such manner, moreover, that upon restoring same, the exact resistance to which the rheostat was set at the time of disestablishment of the current will again be cut in when the current is reestablished. A further object of the invention consists in a rheostat of simple and rugged construction and which may be manufactured at comparatively low cost.

The nature of the invention, however, will best be understood when described in connection with the accompanying drawings, in which—

Fig. 1 is a front elevation of the improved rheostat.

Fig. 2 is an end view thereof.

Fig. 3 is a plan view.

Fig. 4 is a vertical section thru the rheostat.

Similar characters of reference designate corresponding parts thruout the several views.

Referring to the drawings, 10 designates a suitable support or base having two uprights 11 and 12 at its respective ends and within which is mounted for rotation a metallic shaft 13. This shaft is provided at one end with a knob 14 whereby said shaft may be conveniently rotated, and carries a drum 15 upon the periphery of which is wound a resistance wire 16 in the form of a helix of fine pitch. The one end of said coil is embedded in the drum and the other is electrically connected with the shaft 13 (as shown in Fig. 4) and against one end of which shaft bears a spring 17 secured to the base and thru which electrical connection may be made to the rheostat.

A rod 20 is also mounted in the uprights 11 and 12 for oscillation therein, being provided at one end with a knob 21 to conveniently effect this oscillation; and its opposite end being squared and having bearing thereon a flat spring 22 serving to lock the rod in different positions as well as to connect same electrically to an external source of current supply (not shown).

A slider or brush 25 is carried by the rod 20, being in the nature of a tube encircling same and having a spring tongue 26 bearing upon a portion of the surface of the rod to resiliently hold the slider thereto. The slider carries also a brush portion having an edge 27 of thickness substantially equal to the spacing of the wire 16 of the helix and adapted to fit between two successive convolutions thereof and contacting simultaneously with both. It will be apparent that if the drum 15 be rotated, as by turning knob 14, the slider 25 thru engagement of its edge 27 with the convolutions of the wire coil 16 will be advanced or retracted accordingly and will thus cut in or out resistance as may be desired. It will be noted also that the change of resistance is continuous, that is to say in minute fractions of a turn and not in complete turns as is the usual practice where a brush moves over the surface of the turns. Thru the engagement of spring 22 with the squared end of rod 20, the proper position of engagement of brush 27 and the helix 16 will be insured and the brush edge held therein against lateral displacement during rotation of the drum.

Furthermore, if it be desired to temporarily cut off the supply of current, the same may readily be effected by turning the rod 20 thru the knob 21, as this will cause the edge 27 to swing out of engagement with the particular pair of convolutions of the resistance wire and thus interrupt the circuit at this point. The relation of the edge 27 with respect to the resistance coil, however, is not disturbed thereby; and as soon as the rod 20 is turned back to cause engagement again between edge 27 and the coil, the exact amount of resistance to which the rheostat had previously been adjusted will be restored so that it is not necessary to

further manipulate the rheostat after the proper adjustment for the lamp has once been determined.

I claim:—

5. 1. A rheostat, comprising a rotatable drum, a helix of resistance wire wound thereon, a rod parallel to the axis of the rotatable drum and oscillatable in a plane at right angles thereto, a member mounted to slide freely on said rod and having an extension whose edge is adapted to fit between two successive convolutions of the helix to be advanced thereby in either direction as the drum is correspondingly 10 rotated and thereby to increase or decrease the effective resistance of the helix, said 15 slidably mounted member being movable into and out of contact with the helix by correspondingly turning said rod, and electrical connections to the helix and slider.
2. A rheostat, comprising a rotatable drum, a helix of resistance wire wound thereon, an oscillatable rod squared at one end, a knob at the other end thereof for oscillating the rod, a flat spring bearing against the squared end of said rod, and a member 25 slidably mounted on the rod and having an extension whose edge is adapted to fit between and contact with two successive convolutions of the helix.
30. 3. A rheostat, comprising a rotatable drum, a helix of resistance wire wound thereon, an oscillatable rod squared at one end, a knob at the other end thereof for

oscillating the rod, a flat spring bearing 35 against the squared end of said rod, a member slidably mounted on the rod and having an extension whose edge is adapted to fit between and contact with two successive convolutions of the helix, and electrical 40 connections to said helix and said flat spring.

4. A rheostat, comprising a frame, a metallic shaft rotatably mounted therein and projecting at one end thru the frame, a knob secured to the other end for rotating 45 said shaft; a brush bearing against the projecting end of the shaft for effecting electrical connection thereto, a drum mounted on the shaft, a helix of resistance wire wound on the periphery thereof, one end being 50 connected to the metallic shaft, a rod mounted to oscillate in said frame, one end projecting beyond the frame and squared, a knob at the other end for oscillating said rod, a flat spring bearing against the squared 55 end of the shaft and thru which electrical connection may be made thereto, and a tube movably mounted on the rod and having a spring tongue for resiliently holding same thereto, said tube having also an extension 60 whose edge is adapted to fit between and contact with two successive convolutions of the helix.

Signed at Long Island City in the county of Queens and State of New York this 13th 65 day of May A. D. 1922.

ANTON STÖGER.
